UNITED STATES PATENT OFFICE.

FREDERICK S. CHASE, OF WATERBURY, CONNECTICUT.

BASIN-PLUG THIMBLE.

SPECIFICATION forming part of Letters Patent No. 605,813, dated June 14, 1898.

Application filed November 22, 1897. Serial No. 659,424. (No model.)

To all whom it may concern:

Be it known that I, FREDERICK S. CHASE, of Waterbury, in the county of New Haven and State of Connecticut, have invented a new Improvement in Basin-Plug Thimbles; and I do hereby declare the following, when taken in connection with the accompanying drawings and the letters of reference marked thereon, to be a full, clear, and exact description of the same, and which said drawings constitute part of this specification, and represent, in—

Figure 1, a view in side elevation of a basin-plug thimble constructed in accordance with my invention; Fig. 2, a view thereof in vertical section showing it coupled to a discharge-pipe; Fig. 3, a detached plan view of the strainer after it has been flattened out; Fig. 4, a broken sectional view showing the strainer after its initial introduction into the basin-plug thimble, but before it has been flattened out to permanently connect it thereto.

My invention relates to an improvement in basin-plug thimbles, the object being to produce a simple, cheap, and effective article.

With these ends in view my invention consists in a basin-plug thimble having certain details of construction and combinations of parts, as will be hereinafter described, and pointed out in the claims.

In carrying out my invention as herein shown I form a sheet-metal strainer A, with two corresponding oppositely-projecting flanges A' A', respectively adapted to enter horizontal overflow-openings B B, located opposite each other and formed in the upper portion of the basin-plug thimble B', which is formed of sheet metal and provided at its upper end with an outwardly-turned flange B² and having its lower end formed with external screw-threads B³. Preparatory to the introduction of the strainer into the thimble it is concaved, so as to permit the initial entrance of its flanges A' A' into the said overflow-openings B B. When in this position, the strainer is flattened, causing its virtual extension, whereby its flanges are moved outward into the said openings, as shown in Fig. 2, so that the strainer is as effectually secured in place as though it were soldered to the thimble, from which it cannot be removed

unless it is concaved or otherwise bent, so as to virtually reduce its length and withdraw its flanges from the said openings, which, however, are not occupied or filled up by the said flanges to a sufficient extent to prevent them from acting as overflow-openings in the usual way. It will be an easy matter to construct the strainer so that when flattened out it will impinge against the sides of the thimble, so as to be firmly held in place; but even if it should be loose it cannot move except within very narrow limits, as its flanges cannot be got out of the openings.

In carrying out my invention I by preference also turn the lower edge of the thimble inward to form a bearing-flange B⁴, which rests upon the washer C, which in turn rests upon the outwardly-turned flange D of the discharge-pipe E, which is coupled to the thimble by means of an internally-threaded coupling-ring F, which engages with the threads B⁵ and with the flange D, as shown. The flange B⁴ forms a wide bearing for the washer, and not only increases the effectiveness of the joint between the thimble and discharge-pipe, but also prevents the washer from being cut by the lower edge of the thimble.

I would have it understood that I do not limit myself to the exact construction shown and described, but hold myself at liberty to make such changes and alterations as fairly fall within the spirit and scope of my invention. Thus instead of utilizing the overflow-openings for the reception of the strainer-flange I might form special openings in the thimble for the said flanges.

Having fully-described my invention, what I claim as new, and desire to secure by Letters Patent, is—

1. A basin-plug thimble formed with two openings located opposite each other, and containing a sheet-metal strainer provided with flanges adapted to enter the said openings with which they are permanently engaged by flattening the strainer, which is concaved to permit its initial assemblage with the thimble.

2. A basin-plug thimble formed from sheet metal, having its upper end flanged and its lower end externally threaded, and formed

at opposite points with two horizontally-ar-
ranged openings, and containing a sheet-
metal strainer formed with two oppositely-
projecting flanges adapted to enter the said
5 openings with which they are engaged by
flattening the strainer, which is concaved for
its initial introduction into the thimble.

In testimony whereof I have signed this
specification in the presence of two subscrib-
ing witnesses.

FREDERICK S. CHASE.
